UNITED STATES PATENT OFFICE.

CHARLES H. CROWELL, OF BROOKLYN, NEW YORK.

MARKED GUMMED TAPE.

Application filed July 21, 1922. Serial No. 576,572.

To all whom it may concern:

Be it known that I, CHARLES H. CROWELL, a citizen of the United States, and resident of the borough of Brooklyn, county of Kings, city and State of New York, have made a certain new and useful invention relating to Marked Gummed Tape, of which the following is a specification, taken in connection with the accompanying drawing.

This invention relates especially to paper or cloth gummed tape in which separated or other lines or other trade mark or designating markings have preferably been applied to the backing fabric before the adhesive gum coating has been applied thereto. When such a marking coating of water soluble or water medium dyeing marking material is applied to the front face of the backing fabric the water medium naturally carries the aniline or other water soluble dye into the backing fabric especially where the usual uncoated and more or less open kraft papers are used for this purpose. This marking material which may have starch or the like incorporated therewith to give it increased body, may be dried quickly on the front face of the backing fabric and then when the glue or other gum coating is applied in the regular way strong and reliable adherence is secured throughout the backing fabric, including those parts which are more or less covered by this marking coating. The strength of the adhesive gum coating is not, therefore, seriously impaired and such a manufacturer's trade mark or other marking at once shows that it has been applied during the process of manufacture so that it cannot be successfully imitated by any method of marking the manufactured tape.

Such a marking, which is incorporated not only in the backing fabric, but in the adhesive gum coating also gives an important check against fraudulent replacement of the tape on packages or articles sealed with such gummed tape since any attempt to soak off the tape tends to decidedly increase the penetration of the dyeing material of the marking into the backing fabric and of course any inaccuracy of alignment in replacing the gummed tape on the package can be readily detected by careful subsequent ex-

amination if the gum coating has been torn off or separated from the backing fabric of the gummed tape.

In the accompanying drawing showing in 55 a somewhat diagrammatic way illustrative embodiments of this invention:

Fig. 1 is a perspective view of such tape.

Fig. 2 is an enlarged diagrammatic cross section therethrough, and

Fig. 3 is a similar sectional view.

In applying such trade mark or other designating markings to more or less filled cloth or preferably to paper backing fabric any suitable water soluble or water medium marking material may be used, preferably containing at least some readily soluble coloring matter or dye stuff such as aniline dyes. In many cases it is desirable to give additional body to the marking material 65 which may be effectively done by incorporating glue, gum or other adhesive or starchy material therein and for this purpose about a half pound of tapioca flour or a half to three-quarters of a pound of corn-starch may be used in making up a gallon of the marking material, these starchy materials being preferably boiled in the usual way to increase the consistency and adherence thereof. In some cases, however, glue 70 or other adhesive gum may be used to give body to the colored marking material so that this colored adhesive composition may, if desired, be given substantially the same strength and adhesiveness as the regular 75 gum coating on the backing. Any suitable dyeing or coloring material may be incorporated such as a quarter or a half ounce more or less of basic aniline coloring material per gallon, which is sufficient when properly applied to cover approximately one thousand to two thousand square feet of surface, depending of course on the degree of absorbency or roughness of the kraft paper or other backing material to which it is applied. 80 This makes not only an effective, but a very cheap marking material for this purpose since it can be made up for about ten to forty cents or so per gallon, depending upon the particular color and depth of tint desired. 85

As shown in Figs. 1 and 2, the backing fabric 3 is first printed or impressed with

these trade mark or other designating markings 2 which may be repeated at intervals along the length and width of the backing and when the impressions are dry they may 5 in some cases have at least some thickness which is somewhat exaggerated in the impressions 2 in Fig. 2. In addition, the water solution of dye stuff penetrates or stains the adjacent front face of the backing fabric itself so as to dye or color the same throughout the adjacent area indicated at 10 4. Then when the adhesive gum coating 1 is applied to this front face of the backing fabric it adheres strongly not only to the 15 exposed portions of the kraft paper or other fabric, but also throughout these designating markings, the water soluble dye stuff also penetrating the gum coating to an appreciable extent, depending naturally on the 20 thickness or viscosity of the glue or other gum coating when it is applied to the backing. When this gum coating is properly dried in any suitable way the gummed fabric may be cut or slit into the usual narrow 25 strips indicated in Fig. 1 in which the trade mark or other designating markings 2 may recur at the desired intervals along the strip of a few inches more or less apart.

Such marked gummed tape may be used 30 in the regular way for sealing packages or articles such as corrugated paper board cartons or containers and the penetration of the marking material into both the gum coating and the backing paper or other fabric 35 definitely identifies the gummed tape of the particular manufacturer so that its origin can be definitely established in case of failure of the tape or unauthorized opening of the packages. Such tape is also of 40 advantage for non-pilfering reasons since if the tape is torn off and reapplied the slightest difference of alignment or registry usually becomes apparent because of the 45 double impression of these designating markings which would tend to be transferred from one element of the tape to the other. Also if the tape is soaked off this double impression or misalignment is also apparent in many cases and in addition the 50 thorough dampening of the rear face of the backing material of the tape is apt to greatly increase the penetration of the aniline or other soluble dye stuff in these markings so that as indicated in Fig. 3, these additional 55 colored areas or portions 5 which sometimes even penetrate to the rear surface of the backing material give a definite indication of such unauthorized tampering or other dampening action.

60 This invention has been disclosed in connection with a number of illustrative embodiments, forms, materials, proportions and methods of preparation and use, to the details of which disclosure the invention is not 65 of course to be limited since what is claimed

as new and what is desired to be secured by Letters Patent is set forth in the appended claims:

1. The gummed tape comprising an absorbent kraft paper backing and an adhesive gum coating applied thereto and a series of spaced superficial designating markings on said tape between said backing and gum coating and penetrating the adjacent portions of said coating and backing, 70 said markings comprising starchy body material and incorporated water soluble aniline dye stuff adapted to further penetrate the backing if it is moistened.

2. The gummed tape comprising an absorbent paper backing and an adhesive gum coating applied thereto and a series of superficial designating markings on said tape between said backing and gum coating penetrating the adjacent portions of said coating 85 and backing, said markings comprising incorporated water soluble aniline dye stuff adapted to further penetrate the backing if it is moistened.

3. The gummed tape comprising an absorbent paper backing and an adhesive gum coating applied thereto and a series of designating markings on said tape between said backing and gum coating and penetrating only the front portions of said backing fabric adjacent the gum coating, said markings comprising body material and incorporated water soluble aniline dye stuff adapted to further penetrate the backing fabric if it is moistened. 95

4. The gummed tape comprising backing and an adhesive gum coating applied thereto and superficial designating markings on said tape between said backing and gum coating and penetrating only the adjacent 105 front surface portions of said backing, said markings comprising body material and incorporated water soluble dye stuff.

5. The gummed tape comprising absorbent backing and an adhesive gum coating applied thereto and superficial designating markings on said tape beneath said gum coating and penetrating only the portions of said backing adjacent the gum coating, 110 said markings comprising adhesive body material and incorporated water soluble aniline dye stuff adapted to further penetrate the backing fabric if it is moistened. 115

6. The gummed tape comprising absorbent backing and an adhesive gum coating applied thereto and designating markings on said backing coloring adjacent portions of said backing and coating and said markings comprising water soluble dye stuff. 120

7. The gummed tape comprising absorbent paper backing and an adhesive gum coating applied thereto and superficial designating markings on said backing penetrating the backing and coating adjacent said gum coating and comprising water soluble color- 125

ing water adapted to further penetrate the backing if it is moistened.

8. The gummed tape comprising an absorbent backing, designating markings on one face of said backing and comprising water soluble coloring matter penetrating to less than the thickness of the absorbent backing so as to not show through the backing

under ordinary use but adapted to penetrate further and show at the other surface of the 10 backing if the backing is moistened and an adhesive gum coating covering the face of the backing and the markings thereon for securing the tape with the markings concealed.

CHARLES H. CROWELL.
